UNITED STATES PATENT OFFICE.

JOSEPH M. BARRETT, OF FOSTORIA, OHIO, ASSIGNOR TO THE "S-C" REGULATOR MANUFACTURING COMPANY, OF FOSTORIA, OHIO, A CORPORATION OF OHIO.

CONDENSATION TRAP.

Application filed December 1, 1921. Serial No. 519,171.

This invention relates to steam traps, and is particularly concerned with the provision of simple and effective means for draining condensation from steam lines.

5 The usual practice for removing condensation from steam lines, especially in non-return systems, has been to employ a steam trap which discharges condensation into a hot well, and then to utilize an injector, or 10 pump, for returning such water to the boiler. Much difficulty has been experienced in obtaining a trap which operates satisfactorily at various ranges in pressure, without entailing a loss of steam either during, 15 or immediately after the period of discharge. In the intermittent and continuous types of traps, particularly the "bucket" and "float" type respectively, sediment, or boiler scale, frequently lodges between the valve and seat, 20 thus scoring the seats and cutting grooves therein so that they become what is commonly termed "wire-drawn".

Another type of intermittent trap, called 25 the "thermostatic", has been employed for removing condensation, but it has been found that the cost of maintenance for this type of trap is usually high, and that the 30 operation is not entirely satisfactory. Some of the causes of the unsatisfactory operation 35 are, that the valves actuated by mechanical connection with the thermostatic element do not seat properly, and that the thermostatic elements are not sufficiently sensitive to close the valve without permitting steam to escape.

One of the objects of my invention therefore, is the provision of a trap which secures the beneficial results of an intermittently operating trap in that the rapidity and volume 40 of the discharge is employed for ejecting sediment and particles of scale brought down from the receiver; and which possesses positiveness in operation, such as is incident to the thermostatic type, without employing a 45 thermostatic element adjacent the discharge port, and without having a mechanical connection between the thermostatic element and the operating valve.

Another object is the provision of a thermostatically controlled steam trap wherein 50 the discharge valve may be positioned at a point remote from the thermostatic element. In this way, my invention contemplates the construction of a trap which is well adapted 55 for installation in existing systems, partic-

ularly those wherein a receiver is placed in a pit and is inaccessible for the installation and maintenance of the usual non-return steam traps.

Other objects include the construction of 60 a trap, which has few moving parts, which is compact and adapted to be readily attached to existing steam lines, and which has a high efficiency in operation.

In accomplishing the above objects, I provide 65 a steam trap which is dependent for its operation upon the relative difference in temperature between the condensation and steam in the system to be drained, which difference is employed for varying fluid 70 pressure in a secondary chamber. This change of pressure in the secondary chamber is thereafter utilized for actuating a diaphragm, which in turn controls a discharge valve at a point either, adjacent to, 75 or remote from, the condensations receiver.

The means for accomplishing the above 80 objects will be more fully set forth in the following description which relates to the drawings, and the essential characteristics 85 of my invention will be summarized in the claims.

In the drawings, Fig. 1 is a side elevation of a receiver having a steam trap embodying my invention secured thereto; Fig. 2, is an 85 end elevation of such trap and receiver; Fig. 3 is a vertical section partly in elevation taken longitudinally through what is termed a "generator"; and Fig. 4 is a vertical section taken through the preferred form of discharge valve.

Designating the parts shown in the drawings by the use of reference characters, 10 represents a receiver which receives condensation from risers 11, and which is provided with a discharge conduit 12, leading either to a hot well or to a waste water drain. My steam trap comprises what is termed a "generator" which is positioned adjacent the normal level of water within the receiver, 100 and which is adapted to actuate a valve by the difference in temperature between the water and steam. This, in effect, constitutes a thermostatic trap in that the operation is dependent upon the temperature difference 105 of water and steam; but the discharge, instead of being adjacent the generator, may be positioned at a point remote therefrom and satisfactorily operated, as will be herein-after described.

While I have illustrated my invention in connection with the receiver of a heating system, it is of course understood that it is applicable for use in draining the condensation from high pressure lines, either collectively from a common receiver or individually from separators or drain pockets.

Extending laterally from the receiver 10, I provide conduits 13 and 14 which are connected above and below, respectively, the normal level of water within the receiver. These conduits, then, are positioned in planes usually employed for attaching a gauge glass; but for best results, it is advisable to position the conduit 14 near the bottom of the receiver. The outer ends of the conduits 13 and 14 are connected through sections 16, 18, 17 and 19 respectively and are so arranged that the normal level of water within the receiver 10 is on a horizontal plane with some portion of the conduit 18. The conduit 17 may be connected directly to the conduit 14, but I prefer to provide a water leg by utilizing the extension piece 19, for the purpose of cooling the water within the line 18, and maintaining it at a lower temperature than the water at a similar level within the receiver. This is an important factor for securing satisfactory operation because of the fact that the generator is dependent for its use upon the difference in temperature between the water and steam within the tube 18.

The generator 15 shown (the specific construction of which will be claimed in a pending application of mine) comprises a substantially cylindrical member 20 having the ends thereof closed, and secured at 21 and 22 to the tube 18. The interior of this generator is adapted to be filled with water, or any other liquid which vaporizes at comparatively low temperature, so that the pressure within such generator changes very readily with the changes in temperature and heat content of the fluid within the tube 18. A series of annular radiating vanes 23, may project laterally from the generator and may be employed for conducting heat from the member 20. In this way, changes in temperature within the tube 18, caused by the rise and fall of water within the receiver, are quickly employed for changing the temperature, and consequently the pressure of the liquid within the generator 15.

Extending from the lower end of the generator I provide a conduit 25 which communicates with a chamber on one side of a diaphragm 26, in a discharge valve indicated generally at 27. The lower side of the diaphragm is adapted to be engaged by a plate 28 which may be held thereagainst by a spring 29, and which may be arranged to carry a valve 30. This valve 30 is positioned across the discharge conduit 12 and is adapted to engage a seat

31 for controlling the flow of condensation from the receiver. This particular form of valve has been found to be satisfactory for permitting a free discharge, and for responding quickly to variations in pressure 70 within the generator.

The interior of the generator, and the interior of the conduit 25 is filled with water, and then the generator is sealed as by the threaded plug 32. Normally then, the force of the spring 29 is greater than the fluid pressure within the generator, so that the valve 30 is held away from the seat 31, so that condensation flows by gravity to the receiver and is allowed to flow 80 through the discharge valve 27. As soon as steam enters the receiver, and occupies the tube 18 however, then the heat in such steam evaporates the liquid in the generator and thereby creates a fluid pressure which acts against the diaphragm 26 and overcomes the force of the spring 29 thereby forcing the valve 30 against the seat 31. The valve remains in closed position until water thereafter accumulates in the receiver 90 and rises within the conduit 18 thereby displacing the steam therein.

Since by reason of the extension member 19, the water within the conduit 18 is cooler than the steam, then it follows that the temperature, and hence the pressure, of the fluid within the generator is lowered. This reduction in pressure continues until it reaches a point where the force exerted on one side of the diaphragm is less than the force exerted by the spring 29, whereupon the diaphragm is caused to move upwardly and the valve 30 is opened. Then as the water recedes within the receiver, steam is again brought into contact with the generator and the pressure therein is increased, whereupon the valve is again closed.

The relation between the strength of the spring 29 and the position of the tube 18 may be adjusted so that the valve 27 may be actuated by a variation in pressure of only a few ounces within the generator, and so that the valve may allow the escape of condensation without breaking the water seal and permitting steam to escape.

One of the characteristics of this trap is that the valve may be positioned at a considerable distance from the generator. This is often advantageous in cases wherein the receiver is located in a pit, and traps are rendered inaccessible for maintenance and repair. Again this type of trap is well adapted for receiving a pressure gauge which is directly connected to the pressure chamber, and is calibrated to indicate the level of water within the receiver. Accordingly gauge glasses may be dispensed with and the exact status of the condensation in the receiver, at a point remote therefrom, may be obtained.

From the foregoing description, it will be seen that my invention provides a steam trap which has few moving parts, which is positive in operation, and which may be readily attached to existing lines without material changes in piping arrangement. One of the advantages of a trap constructed according to my invention is, that the condensation is positively removed without an ensuing loss in steam, and that the condensation is discharged intermittently, thus insuring a complete cleansing action to the discharge valve. Further, the valve itself may be constructed with a large opening which is highly important in this work, especially in view of the fact that receivers are placed in the lowest points in the line, and consequently are subjected to an accumulation of sediment and scale.

Having thus described my invention what I claim is:—

1. The combination of a receiver adapted to contain water and steam, a conduit providing in part a water leg and communicating with the receiver at points above and below the normal water level thereof, means associated with the conduit responsive to change in heat content of the fluid in the conduit, a discharge valve for the receiver, and means connected to said first named means for actuating said valve.

2. A device for regulating the flow of condensate from a steam trap comprising in combination a discharge valve for the trap, a water leg disposed without the trap and not wholly above the level of the bottom thereof and actuating means for the valve including a thermal responsive element adapted to be subjected to steam when the condensate is at one level and subjected to the comparatively cold water carried in the water leg when the condensate is at another level.

3. A steam trap having in combination a receiver, conduits extending laterally therefrom at points above and below a normal water level within the receiver, a drop leg connected with the lower conduit, a generator disposed intermediate said drop leg and upper conduit, said generator comprising a hollow member surrounding the conduit and forming an independent pressure chamber, a discharge valve for said receiver having a pressure responsive element, a spring tending to open the valve and a tube connecting the generator with a diaphragm chamber of the valve and a diaphragm acting on the pressure responsive element of the valve whereby variations in temperature within the generator will effect a variation in the pressure within the tube and thereby cause the diaphragm and spring to vary the amount of opening of the valve.

4. In a device of the character described, the combination of a receiver, a conduit in the form of a loop depending below the lower level of the receiver chamber and connected to the receiver at points above and below the normal water level of the receiver, pressure generator means associated with the conduit intersecting the plane of the normal water level of the receiver, a discharge valve for said receiver having a spring tending to keep the valve open and a pressure responsive element adapted to close the valve, a pressure conduit connecting the last named element with the pressure generator means, so that changes in the heat content of the fluid in the first named conduit effect changes in the pressure exerted on the pressure responsive element to vary the status of the valve.

In testimony whereof, I hereunto affix my signature.

JOSEPH M. BARRETT.
